UNITED STATES PATENT AND TRADEMARK OFFICE
Certificate

Patent No. D. 429,767

Patented: August 22, 2000

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Chuck Morrison, Charlotte, NC; and Edward G. Battle, Winston-Salem, NC.

Signed and Sealed this Seventh Day of February 2006.

ALAN P. DOUGLAS
Supervisory Patent Examiner
Art Unit 2911
